BUILDING STRUCTURE

Charles A. Searing, Pittsburgh, Pa.

Application July 5, 1935, Serial No. 29,770

6 Claims. (Cl. 72—41)

My invention relates to that type of building structure wherein walls of bricks or tiles are employed, and is herein described as used in connection with buildings having a framework of steel, but certain features of the invention are applicable also to the walls of other types of buildings.

One object of my invention is to provide a brick or tile wall of such form that various of the tiles can be anchored directly to a steel framework, notwithstanding variation in spacing as between various members of the frame structure.

Another object of my invention is to provide a wall of the character referred to wherein the individual blocks may not only have direct interlocking engagement with the framework, but are interlocked with one another, and can be readily placed in accurate alignment with respect to both the framework and one another.

Another object of my invention is to provide a wall structure comprising cored or apertured tiles, with improved means for sealing said apertures at the edges or ends of the tiles, to thereby provide dead air spaces.

Another object of my invention is to provide a masonry wall structure having improved joint material between the blocks or tiles comprising the wall.

Some of the forms which my invention may take are shown in the accompanying drawings, wherein Figure 1 is a sectional plan view of a wall structure; Fig. 2 is a face view thereof; Fig. 3 is a view, on an enlarged scale, of a portion of the structure of Fig. 1; Fig. 4 is a view taken on the line IV—IV of Fig. 3; Fig. 5 is a plan view showing one of the window jamb blocks of Fig. 2; Fig. 6 is a plan view of another jamb block; Fig. 7 is an enlarged view taken on the line VII—VII of Fig. 2; Fig. 8 is an enlarged view taken on the line VIII—VIII of Fig. 2, and Fig. 9 is a plan view showing one of the joint strips employed between the horizontal courses of the bricks.

The invention is shown as employed in connection with a building structure having steel framework, provided with vertically-extending I-beams 11, which may be connected by horizontally-extending beams at various floor levels in the usual manner.

The bricks or tiles employed in constructing the walls may be of any ordinary tile or brick material, and may suitably be of burned shale or fire clay.

An important feature of my invention resides in the form of tiles or bricks employed. A major

portion of the wall is composed of tiles formed as shown more clearly in Fig. 3. These tiles 12 have cored openings 13, 14 and 15, all extending entirely through the tiles, in a vertical direction. The cored openings 14 serve primarily as dead air spaces when covered with a "mortar" joint, as hereinafter explained.

The openings 13 may also function somewhat as dead air spaces, but principally serve as a means for anchoring the pointing mortar in place, as hereinafter explained. The openings 15 will also serve as dead air spaces. Each tile is provided with three vertically-extending flanges 16, 17 and 18 that serve as hook elements for locking the tiles to the I-beams or studs 11.

Each of the tiles 12 is provided with a tongue 19 and a groove 20, the tongue of one tile interfitting with the groove of an adjacent tile, so that those tiles which are intermediate adjacent I-beams 11 will be held in place. The tongues or grooves also facilitate the assembling of the tiles in proper alignment in a wall.

The tiles may conveniently be made in 12 inch lengths, and the tongues 16 and 17, for example, may suitably be 6 inches apart, so that the tiles will fit in framework wherein the vertical frame members 11 are spaced apart distances which are multiples of 6 inches. Where the tiles 12 of one course are placed in staggered or offset relation with the tiles of the adjacent courses as shown in Fig. 2, and as is common practice in the brick-laying art, if the tongues 17 of the tiles in one course engage with certain of the I-beams 11, as shown in Fig. 3, on the succeeding course, the tongues 16 of the upper tiles would have interlocking engagement with said beams. It will also be seen that if the beams in Figs. 1 and 3 were brought either closer together or farther apart by distances of 6 inches or 12 inches, they could still be engaged by tongues 16, 17 or 18, in various of the courses.

It will, of course, be understood that the tiles need not be made in lengths which are multiples of a 6-inch dimension, but that they could be made in various other lengths, such as 4-inch multiples or 8-inch multiples, etc., where they are to be used with frame members or I-beams which have spacing of 4-inch multiple or 8-inch multiple.

The blocks 21 and 22 which are positioned at the sides of the door or window jamb openings, as shown in Fig. 2, are formed somewhat in the same manner as the tiles 12, but each has one of its ends plain, as shown in Figs. 5 and 6,

and the tiles 22 are, of course, only about one-half the length of the tiles 21.

Corner blocks 23 may all be formed in duplicate, and are each provided with a tongue 24, 5 that engages with a flange of a corner I-beam 11, when the tiles are placed, as shown in Fig. 7. In alternate courses, the corner blocks will be placed in the position shown in Fig. 8, so as to 10 secure the desired staggered arrangement of the vertical joints, and consequent binding effect as between the various courses. The tiles 23 are cored in substantially the same manner as the tiles 12.

The cored openings and the flanges of the 15 various tiles all extend in parallelism with one another, so that the tiles can be cheaply made by the extrusion process, it being necessary only to provide an extrusion die within which are positioned suitable core bars and flange bars for 20 forming the cored openings and the hook flanges of the tiles.

Another important feature of my invention resides in the form of "mortar" joint employed. 25 When each course of tiles has been laid, a pre-formed joint strip 26 of what might be termed mortar is placed on the course, and is of such width as to overlie the cored openings 14 and 15, thus producing dead air spaces within the tiles. The joint strips will be cut away at one 30 edge in the vicinity of the studding 11, as shown in Fig. 9, and will fit against the studding, thus facilitating the placement thereof in proper position on the tiles. Joint strips may suitably be formed of 80% to 90% fire clay, with an asphalt 35 and oil binder of 10% to 20%. The binder may suitably be composed of about 80% asphalt and 20% mineral oil. A heavy mineral oil sludge could be employed as a binder. In any event, it is desired to have the joint strip of such 40 material that it will yield slightly under the weight of the superposed tiles, so that unevennesses in the edges of the tiles may be compensated for, and an air and moisture-tight seal effected.

The strips 26, preferably terminate at the 45 cored openings 13, and pointing mortar 27 of the usual lime and sand, or cement composition, or a tinted mortar, is introduced into the horizontal and vertical joint spaces at the face of the wall. As shown more clearly in Fig. 4, the 50 mortar 27 will spread somewhat into the openings 13, whereby it will be keyed in place, and also serve to key the tiles together. The mortar may be applied with a trowel or extruded into the joints through a nozzle, under pressure. The 55 pointing mortar will ordinarily not be applied until after any slight yielding of the joint strips under load has taken place, which may be within a period of a few hours, or longer, depending upon weather conditions and the stiffness of the 60 material in the joint strips.

I claim as my invention:

1. A building structure comprising frame members having vertically arranged flanges, and tiles having flanges on their rear sides, at points adjacent to their ends and at intermediate points, the abutting ends of adjacent tiles having offsets 5 which have interfitting engagement with one another, and certain of the tiles having their intermediate flanges in hooked engagement with the frame flanges and other tiles having their end flanges hooked to the said frame flanges. 10

2. A building structure comprising frame members having vertically arranged flanges, and tiles each having a flange on one of its sides, in hooked engagement with a frame flange, the abutting ends of adjacent tiles having offsets 15 which have interfitting engagement with one another.

3. A building structure comprising frame members having vertically arranged flanges, tiles arranged in courses, and certain of the tiles 20 each having a flange on one side at a point approximately midway between its ends and in hooked engagement with a frame flange, the abutting ends of adjacent tiles having offsets 25 which are in interfitting engagement with one another.

4. A building structure comprising frame members having vertically arranged flanges, tiles having flanges adjacent to their ends and their mid-points, the tiles of certain courses having 30 their intermediate flanges in hooked engagement with the first-named flanges and the tiles of other courses having their end flanges so hooked, and strips of water-resistant plastic material interposed between adjacent courses of tile. 35

5. A building structure comprising frame members having vertically arranged flanges, tiles arranged in courses and having flanges adjacent to their ends and their mid-points, the tiles of certain courses having their intermediate flanges 40 in hooked engagement with the first-named flanges and the tiles of other courses having their end flanges so hooked, and strips of water-resistant plastic material interposed between adjacent courses of tile, the tiles having openings 45 extending vertically therethrough and sealed by said strips.

6. A building structure comprising frame members provided with vertically arranged flanges, and tiles assembled in courses with the 50 tiles of certain courses off-set longitudinally relative to the tiles of adjacent courses, the tiles of certain courses having flanges adjacent to their ends in hooked engagement with flanges of the frame members, and the tiles of intermediate off-set courses having flanges at their 55 mid-points in hooked engagement with said flanges of the frame members.

CHARLES A. SEARING. 60
